Thomas H. Duzan Inventor
By his Attorney, J. W. Lehman.

UNITED STATES PATENT OFFICE.

THOMAS H. DUZAN, OF PALESTINE, TEXAS.

DUST-GUARD FOR CAR-WINDOWS.

SPECIFICATION forming part of Letters Patent No. 363,125, dated May 17, 1887.

Application filed March 18, 1887. Serial No. 231,428. (No model.)

To all whom it may concern:

Be it known that I, THOMAS H. DUZAN, a citizen of the United States, residing at Palestine, in the county of Anderson and State of Texas, have invented certain new and useful Improvements in Dust-Guards for Car-Windows; and I do hereby declare the following to be a full, clear, and exact description of the invention, such as will enable others skilled in the art to which it appertains to make and use the same.

My invention relates to that class of devices which are designed to prevent the entrance of cinders or sparks into the windows of railway-cars; and the object of my invention is to produce an attachment which shall be of simple form or construction, and which may be readily attached to or removed from the frame of a car-window, and which shall serve to collect the cinders, or sparks, or dust and discharge them underneath the car-window during the progress of the train.

To the above purposes my invention consists in the peculiar and novel form and location of the guard or cinder-arrester, as hereinafter described and claimed.

In order that my invention may be fully understood, I will proceed to describe it with reference to the accompanying drawings, in which—

Figure 1 is a side elevation of a sleeping-car with my improvements attached thereto. Fig. 2 is a vertical section of one of the car-windows, showing the escutcheon for receiving the guard. Fig. 3 is a perspective view of the guard.

In the said drawings, A designates one of the windows of a passenger-car, which is provided with two recesses or grooves, a a', to receive two frames or sashes, B B', such double sashes being ordinarily used for sleeping-cars, to which my invention is particularly intended to be applied.

In the outer groove or recess, a, is placed an escutcheon, b, having a hole, b', from which a slot, b'', extends downwardly, as shown.

C designates the guard, which is of concavo-convex form, having its upper end closed by a transverse portion, c, and having its lower end formed with an inclined portion, c', leading to and terminating in an opening, c'', as shown. The edge c' of the guard is provided with a strip, d, of wood or other suitable ma-

terial, and upon the outer side of this strip is placed a stud, d' which is designed to be inserted into the escutcheon b and brought downward into the slot b', for the purpose of holding the guard with its concave side in the direction in which the train or car ordinarily moves. Holes e are formed in the oblique or inclined portion c' of the guard, to receive 60 yarn or any other suitable material, which shall effectively close any opening between the sill f of the car-window and the edge of the inclined portion c' of the guard, so that the sill shall not be injured, it being understood that 65 the pitch of the inclined portion c' corresponds with the pitch of the sill f. By virtue of this arrangement, the smoke, dust, or cinders are drawn into the guard and are discharged from its lower end through the opening c'', as shown 70 in the drawings. The window-frame may be lowered upon the upper end of the guard, so as to permit free ventilation of the car.

Having thus described my invention, what I claim as new, and desire to secure by Letters 75 Patent, is—

1. As an improved article of manufacture, a dust-guard for car-windows, &c., the body of which is of concavo-convex form, closed at its upper end by a transverse plate and provided at its lower end with a contracted opening for the discharge of cinders, dust, &c., said body portion being provided with means, substantially as described, for effecting its attachment to a window-frame, for the purpose 85 specified.

2. An improved dust-guard for railway-cars, consisting of a metallic frame of concavo-convex form, provided with the strip d, having the stud, substantially as described. 90

3. The combination, with the window-frame of a car provided with an escutcheon, b, of a guard of concavo-convex form having its lower end inclined and made with an opening, c'', and its upper end closed by a transverse portion, c, a series of holes, e, designed to receive a cushioning material, substantially as set forth.

In testimony whereof I affix my signature in presence of two witnesses.

THOMAS H. DUZAN.
